UNITED STATES PATENT OFFICE

**HARRY ALPHONSE WIDMER, OF LONDON, ENGLAND, ASSIGNOR TO TUCK-TITE LOCK
AND FASTENER COMPANY LIMITED, OF LONDON, ENGLAND**

DESIGN FOR A FASTENER FOR CONTAINERS

**Application filed May 6, 1931, Serial No. 39,735, and in Great Britain April 27, 1931. Term of patent
14 years.**

To all whom it may concern:

Be it known that I, **HARRY ALPHONSE WIDMER**, residing at 32 to 34, Clerkenwell Road, London, E. C. 1., England, a subject of the King of Great Britain, have invented a new, original, and ornamental Design for a Fastener for Containers, of which the following is a specification, reference being had to the accompanying drawings, forming part thereof, in which

Figure 1 is a plan view on an enlarged scale,

Figure 2 is a side view and

Figure 3 is a back view of the design for a fastener for containers such as ladies' handbags, purses and other articles of like character showing my new design.

I claim:—

The ornamental design for a fastener for containers substantially as shown.

In testimony whereof I have signed my name to this specification.

HARRY ALPHONSE WIDMER.
